(57) **CLAIM**

The ornamental design for a toy shark, as shown and described.

DESCRIPTION

FIG. 1 is a right side view of my design of a toy element;

FIG. 2 is a rear side view thereof;

FIG. 3 is a left side view thereof;

FIG. 4 is a front side view thereof;

FIG. 5 is a bottom view thereof, the portions shown in broken line playing no part in my design;

FIG. 6 is a top view thereof; and,

FIG. 7 is a top perspective view thereof.
